UNITED STATES PATENT OFFICE.

EDWIN F. PIERCE, OF MILWAUKEE, WISCONSIN.

ADJUSTABLE JOINT FOR ELECTRIC-LIGHT FIXTURES.

973,558.

Specification of Letters Patent. Patented Oct. 25, 1910.

Application filed April 12, 1909. Serial No. 489,497.

To all whom it may concern:

Be it known that I, EDWIN F. PIERCE, a citizen of the United States, residing at Milwaukee, county of Milwaukee, and State of Wisconsin, have invented new and useful Improvements in Adjustable Joints for Electric-Light Fixtures, of which the following is a specification.

My invention relates to improvements in adjustable joints for electric light fixtures, and it pertains to that class which are used either with or without gas pipe connections.

The construction of my device is explained by reference to the accompanying drawings, 15 in which—

Figure 1 represents a vertical section and Fig. 2 is a bottom view of an uninsulated adjustable fixture adapted to be connected directly with the ceiling of a room. Fig. 3 20 is a vertical section and Fig. 4 is a bottom view of an insulated adjustable fixture, also connected with the ceiling of a room; and Fig. 5 is a vertical section and Fig. 6 a bottom view of a combined gas and electric 25 light fixture with an adjustable insulated hanger.

Like parts are identified by the same reference figures throughout the several views.

1 is a tubular hanger which is provided at 30 its lower end with a screw threaded bearing 2, by which it is adapted to be coupled with a chandelier, lamp, or other light fixture of ordinary construction. The upper end of the hanger 1 is provided with a spherical shaped member 3, which together with the cup shaped bracket 4 forms a so-called ball and socket joint, which permits the hanger to be freely moved or swung in any direction, as may be required to bring the hanger 35 and fixture suspended therefrom to the vertical regardless of the uneven surface of the ceiling, or the fact that the supporting bracket is out of plumb.

The lower end of the bracket 4 diverges 45 outwardly forming an annular flange 5 terminating at a distance from the lower end of the hanger 2, whereby the required space is provided between the hanger and the opposing surface of the annular flange for the 50 proper movement of the hanger to bring the same to the vertical as stated. The annular flange 5 is provided with a plurality of set screws 6, which contact with the lower end of the hanger 2 and serve to hold the hanger, 55 when adjusted in its proper position. The bracket 4 is open at the top, whereby the

hanger 5 is free to be inserted, preparatory to securing the hanger to the ceiling. In Figs. 1 to 4 inclusive, the bracket 4 is provided with an annular fastening plate 7, 60 which is adapted to be secured to the ceiling of a room by a plurality of screws. 8 are apertures through which the supporting screws are inserted.

In the form shown in Figs. 3 to 5, the 65 hanger 2 is provided at its upper end with an outwardly diverging flange 8 and is surrounded with a spherical shaped insulating bearing 9, the exterior surface of which conforms in shape to the opposing bearing surface 10 of the bracket and the two parts cooperate to form an insulated ball and socket joint, which permits of the lower end of the hanger 2 being inclined as may be required to bring the fixture suspended therefrom to 75 the vertical beneath the bracket.

In the form shown in Figs. 5 and 6, the annular fastening plate 7 is dispensed with and the upper end of the bracket 4 is provided with a threaded coupling sleeve 11, 80 which is adapted to be coupled to the end of a gas pipe from which the fixture is adapted to be suspended. The coupling 11 is provided with screw threaded bearings 12, with which it is connected with a similar threaded bearing formed in the upper end of the bracket 4. 13 is an inwardly diverging annular collar, which is connected with the inner wall of the coupling 11 and terminates centrally above the central duct 14 of the hanger 2, whereby such moisture as may arise from condensation in the gas pipe will be caused to drip into the duct 14 of the hanger. The opposing surfaces of the insulation 9 and the bracket 4 are so ground 90 as to form a tight joint and a spiral spring 15 is interposed between the upper end of the hanger 2 and the lower end of the coupling 11 and serves to retain the hanger in close contact with the supporting bracket, 100 whereby a tight joint is maintained between such parts and the liability of the gas escaping is thereby prevented.

I am aware that light fixtures have heretofore been suspended from ball and socket joints, the sockets of which have been formed in two parts adapted to be separated horizontally at the center of the ball for the reception of the latter. By my improvement, however, the socket or so called bracket 110 is made open at its upper side for the reception of the hanger and for this reason it

becomes unnecessary to form the bracket in separable parts and such parts are by my construction made integrally, whereby the construction is simplified and expense of 5 manufacture diminished.

To prevent the hanger 2 and the spherical member connected therewith from turning in the supporting bearings of said bracket, I have provided said bracket and hanger 10 with closely fitting angular bearings, which are located at the junction of the spherical member with the cylindrical member of such hanger, as more clearly shown in Figs. 2, 4 and 6 of the drawings, whereby the hanger 15 is prevented from turning in the bracket as a gas pipe or other fixture is being secured thereto.

Having thus described my invention, what I claim as new, and desire to secure by Letters Patent, is—

1. In a device of the described class, the combination of a bracket provided on its upper side with a downwardly converging spherical shaped recess for the reception of a spherical member of a hanger, on its lower side with a downwardly diverging recess for the reception of the cylindrical member of such hanger, and at the junction of such recesses with an aperture for the 25 reception of the angular bearings of the hanger, a hanger comprising an upper spherical member and a lower cylindrical member provided at the junction of such members with angular bearings conforming 30 in shape and adapted to fit into the angular bearings of said aperture, whereby said hanger is prevented from turning with said bracket and a plurality of radial adjustable screws having threaded bearings in the 35 downwardly diverging walls of said bracket and adapted to impinge at their inner ends against the central member of said hanger and retain the same at any desired point of 40 adjustment.

2. In adjustable joints for electric light fixtures of the class described, the combination of a bracket provided on its upper side with a downwardly converging spherical shaped recess for the reception of a spherical shaped member of a hanger, and on its lower side with a downwardly diverging recess for the 45 reception of the cylindrical member of such

hanger, a hanger comprising an upper spherical shaped insulating member and a lower cylindrical member suspended in said bracket, a screw threaded coupling having threaded bearings in the upper side of said bracket provided at its lower end with downwardly converging flanges terminating centrally above the central aperture of said hanger and adapted to discharge liquid moisture from above into said aperture, and a plurality of radial adjustable screws having threaded bearings in the downwardly diverging walls of said bracket and adapted to impinge at their inner ends against the central member of said hanger and retain the same at any desired point of adjustment.

3. In adjustable joints for electric light fixtures of the class described, the combination of a bracket provided on its upper side with a downwardly converging spherical shaped recess for the reception of a spherical shaped member of a hanger, and on its lower side with a downwardly diverging recess for the reception of the cylindrical member of such hanger, a hanger comprising an upper spherical shaped member and a lower cylindrical member suspended in said bracket, a screw threaded coupling having threaded bearings in the upper side of said bracket provided at its lower end with downwardly converging flanges terminating centrally above the central aperture of said hanger, a spiral wire spring interposed between said screw threaded coupling and the spherical member of said hanger, a plurality of radial adjustable screws having threaded bearings in the downwardly diverging walls of said bracket and adapted to impinge at their inner ends against the central member of said hanger and retain the same at any desired point of adjustment, means for connecting said bracket with the ceiling of a room and means for suspending light fixtures from said hanger, all substantially as and for the purpose specified.

In testimony whereof I affix my signature in the presence of two witnesses.

EDWIN F. PIERCE.
